UNITED STATES PATENT OFFICE.

DEAN SMITH, OF DAYTON, OHIO, ASSIGNOR, BY MESNE ASSIGNMENTS, TO THEOPHILE DE PORT, OF DAYTON, OHIO.

AEROPLANE.

Application filed December 18, 1920, Serial No. 431,725. Renewed July 20, 1925.

To all whom it may concern:

Be it known that I, DEAN SMITH, a citizen of the United States, residing at Dayton, in the county of Montgomery and State of 5 Ohio, have invented certain new and useful Improvements in Aeroplanes, of which the following is a specification.

This invention relates to aeroplanes or flying machines, and more particularly to the 10 employment of standarized construction and interchangeable parts.

With view to economy of construction, and convenience of repairs and replacements in the event of accident, the present invention 15 contemplates an aeroplane having duplication of parts so far as is feasible, with view to minimizing the number of supply parts to be required and to enable ready substitution thereof.

20 The object of the invention is to simplify the structure as well as the means and mode of operation of such aeroplanes, whereby they will not only be cheapened in construction, but will be more efficient in use, stanch 25 and safe in flight, having few parts and unlikely to get out of repair.

A further object of the invention is to 30 provide an improved form of trussed wing structure employing struts as the truss elements, and minimizing air resistance by eliminating so far as practical, the use of brace wires and other reinforcing means.

A further object of the invention is to 35 provide an improved form of engine mounting and an improved type of rudder and elevator sections, interchangeable one with the other in relation with fixed stabilizer fins.

A further object of the invention is to 40 provide an improved form of landing gears.

With the above primary and other incidental objects in view as will more fully appear in the specification, the invention consists of the features of construction, the parts and combinations thereof, and the mode of 45 operation or their equivalents as hereinafter described and set forth in the claims.

In the drawings, wherein is disclosed the preferred but not the only form of embodiment of the invention, Fig. 1 is a side elevation of the assembled aeroplane partly broken away to disclose the engine mounting. Fig. 2 is a front elevation of the assembled plane. Fig. 3 is a top plan view of the tail portion of the structure. Fig. 4 is a 55 detail perspective view illustrating the rela-

tion of the trussing struts. Fig. 5 is a detail perspective view of the engine mounting. Fig. 6 is a detail view of the engine mounting connection.

Like parts are indicated by similar characters of reference throughout the several views.

The present invention contemplates the production of a small general purpose machine, which may be economically manufactured to be sold at a popular price, and maintained with minimum maintenance expense.

In the type of machine illustrated, 1 is the fuselage of the usual stream line design, having therein the cock pit 2 for the aviator. 70 The machine illustrated in the drawing is a biplane having the wings 3 and 4 of equal extent and identical construction, and capable of being interchanged one for the other.

These wings are supported and interconnected by vertical struts 5, spaced outwardly from the fuselage 1, and extending intermediate the wings 3 and 4 and diagonally disposed strut 6, connected to the upper wing adjacent to the upper end of the vertical struts 5, and extending thence downwardly and inwardly and connected at their opposite ends to the side of the fuselage 1. 75

These struts are substantially N-shaped, comprising the parallel arms 7-7 and the diagonal arm 8. This diagonal arm 8 in each instance is directed upwardly and forwardly, as is indicated particularly in Figs. 1 and 4. The struts 5 and 6 are of equal length and like design, and may be interchanged 80 and substituted one for the other. The construction shown affords a diagonally trussed or braced structure in which each element is capable of transmitting both tension and compression strains.

Likewise, these elements are so arranged as to counteract or offset the strain one upon the other to resist deflection and afford a stable construction without the necessity of brace or guy wires, which are effective in one direction only. The diagonally disposed struts 6 brace the structure laterally, while the diagonal arms 8 of each of the struts affords ample fore and aft bracing effect. As before mentioned the struts 5 and 6 being of identical design and proportion, the structure involves merely the duplication of the same strut in a different position, and therefore like the wing structure necessitates but one style or type of member.

At the rear of the fuselage 1, there 100 105 110

are provided three fixedly attached triangular fin portions 9, 10 and 11. These fin portions have a stabilizing effect. Hinged to each of these stabilizer fins 9, 10 and 11 is a 5 substantially L-shaped section 12. The vertically disposed section 12 carried by the vertical stabilizer fin 9 comprises the guiding rudder, while the like section 12 hinged to the oppositely disposed laterally extending 10 stabilizer fins 10 and 11, comprise the elevator rudder. The rudder elements whether for guiding purposes or elevating purposes to be mounted upon the vertically disposed stabilizer fin 9 or upon the laterally exposed stabilizer fins 10 and 11, are of identical area and outline, and hence comprise but a single style or type of member utilized in multiple and interchangeable in 15 its several locations.

20 This prevailing idea of duplication of interchangeable parts is likewise applied to the ailerons and to the motor mounting at the forward end of the fuselage. The motor is carried upon longitudinally disposed parallel supporting bars 14, from which extend outwardly and both upwardly and downwardly, diagonal brace members 15 and 16. Interposed between the brace members 15 are struts 17. The supporting braces 15 and 16 25 both connect at their rearward ends with the upper and lower covers of the fuselage bulkhead 18, from which extends downwardly and inwardly additional brace members 19 connecting with the inner ends of the supporting bar 14. The supporting bracket structure thus formed extends equally above and below the supporting bars 14 and hence either side of the bracket may be turned upwardly enabling the bracket structure to be 30 employed as either the right or left side of the engine support. The bracket structure thus formed comprising the longitudinal supporting bar 14 and its diagonal braces 15, 16 and 19 and interconnecting strut 17 are 35 detachably connected in pairs to the bulkhead of the fuselage projecting forwardly therefrom. Being reversible and interchangeable as to right and left, a single type and design of supporting member will serve 40 for either side of the engine support and hence involves merely duplication.

45 The landing gear comprises the carrying wheels 22, located slightly in advance of the center of gravity of the structure and connected to the lower supporting wing by the vertical struts 23 and rearwardly and upwardly inclined strut 24, and further braced by the inwardly and upwardly inclined struts 25 extending to a fuselage 1 such landing gear parts being interchangeable. The 50 landing wheels are provided with the usual resilient shock absorbing coils 26.

55 At the tail of the machine there is provided a landing skid 27, pivoted at 28, and having the resilient connection 29 against

the tension of which the skid may yield when contacting with the ground in making a landing or in the event that it encounters an obstruction when taking off. The relation of the resilient connection to the pivotal point of the tail skid, affords increased efficiency and greater leverage than has heretofore been employed.

70 While for illustrative purposes the invention has been shown as embodied in a biplane, it is to be understood that the improvements and features of construction heretofore pointed out are applicable also to a triplane or machines of other multiplane type. A stream line strut as illustrated affords less air resistance than a brace wire of much smaller diameter thereby necessitating less power and increasing the speed of the flight.

75 From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

80 While in order to comply with the statute the invention has been described in language more or less specific as to structural features, it is to be understood that the invention is not limited to the specific details shown, but that the means and construction herein disclosed comprise but one of several modes of 85 putting the invention into effect, and the invention is therefore claimed in any of its forms or modifications within the legitimate and valid scope of the appended claims.

90 Having thus described my invention, I claim:

95 1. In an aeroplane the combination with a fuselage, parallel spaced supporting wings and propelling and guiding means, of vertically disposed parallel struts interposed 100 between the wings on opposite sides of the fuselage, and additional struts equal in length to said vertical struts, inclined downwardly and inwardly with their outer ends attached to the upper supporting wing and their lower ends attached to the fuselage, the vertical and inclined struts being interchangeable one for the other.

110 2. In an aeroplane, the combination with a fuselage, parallel spaced supporting wings and propelling and guiding means, of a plurality of supporting struts and a plurality of brace struts of equal length, the brace struts being inclined in relation to the supporting strut intermediate the supporting wings to afford a trussed structure, the struts comprising said trussing means being interchangeable one for another.

115 3. In an aeroplane, the combination with a

- a fuselage, parallel spaced supporting wings and propelling and guiding means, a plurality of substantially **N** shaped struts connecting the wings one with the other, and 5 to afford a trussing effect, all of said **N** shaped struts being of equal extent and like 50 design and interchangeable one with another.
5. additional **N** shaped struts of equal extent and like design diagonally disposed intermediate the first mentioned struts and interchangeable therewith.
4. In an aeroplane, the combination with 10 a fuselage, parallel spaced supporting wings and propelling and guiding means, of a supporting truss for said wings comprising a plurality of struts of equal length arranged in substantially **M** shaped relation interposed between said wings, the members of 15 such truss being interchangeable one with another.
5. In an aeroplane, the combination with a fuselage, parallel spaced supporting wings 20 and propelling and guiding means, of means for supporting the wings independent of brace wires, comprising a plurality of struts arranged in an **M** shaped formation, to afford a supporting truss therefor, the apex 25 of said **M** shaped formation being attached to and supported upon the fuselage structure.
6. In an aeroplane, the combination with a fuselage, parallel spaced supporting wings 30 and propelling and guiding means, of a plurality of **N** shaped struts interposed between the wings the diagonals of which are inclined downwardly and rearwardly, said **N** shaped struts being arranged in substantially 35 vertical, spaced relation with additional **N** shaped struts divergently arranged intermediate said vertical **N** shaped struts to afford a trussing effect.
7. In an aeroplane, the combination with 40 a fuselage, parallel spaced supporting wings and propelling and guiding means, of a plurality of **N** shaped struts interposed between the wings, the diagonals of which are inclined downwardly and rearwardly, said 45 **N** shaped struts being arranged in substantially vertical spaced relation with additional **N** shaped struts divergently arranged intermediate said vertical **N** shaped struts to afford a trussing effect, all of said **N** shaped struts being of equal extent and like 50 design and interchangeable one with another.
8. In an aeroplane, the combination with a fuselage, a supporting wing, guiding and propelling means including a motor, of a 55 motor mounting comprising a pair of parallel support bars, and divergently disposed brace members extending equally above and below the supporting bars and interconnected therewith and with each other to form 60 interchangeable supporting brackets for the motor, to be detachably mounted on the forward portion of the fuselage structure.
9. In an aeroplane the combination with a fuselage, a supporting wing, guiding and 65 propelling means including a motor, of a pair of separable interchangeable trussed brackets for the motor.
10. In an aeroplane the combination with a fuselage, a supporting wing, guiding and 70 propelling means including a motor, of a reversible trussed supporting member for the motor.
11. In an aeroplane, the combination with a fuselage, a supporting wing, guiding and 75 propelling means including a motor, of a reversible motor bracket to be detachably mounted upon the aeroplane structure, comprising a motor rest and bracing and attachment members extending equally in opposite directions therefrom enabling the bracket to be attached with either side uppermost.
12. In an aeroplane, the combination with a fuselage, a supporting wing, guiding and 80 propelling means including a motor, of a pair of symmetrical supporting brackets for the motor capable of being transposed and reversed and adapted for the engagement of the motor in either position of adjustment.
- In testimony whereof, I have hereunto set my hand this 11th day of October A. D. 1920.
- DEAN SMITH.
